UNITED STATES PATENT OFFICE.

LEONARD SARGEANT, OF FAIRMONT, WEST VIRGINIA.

TRAMROAD.

Application filed October 5, 1922. Serial No. 592,614.

To all whom it may concern:

Be it known that I, LEONARD SARGEANT, a citizen of the United States, residing at Fairmont, in the county of Marion and 5 State of West Virginia, have invented certain new and useful Improvements in Tramroads, of which the following is a specification.

This invention relates to a tie suitable for 10 holding the rails of a tram road to be used, for example, in coal mines or other industrial plants where it is desirable to occasionally move the rail and ties to new positions.

One of the objects of the invention is to 15 provide a tie which will not readily shift laterally from the position in which it is laid.

Another object of the invention is to so 20 connect the tie and rails that they may be readily separated and reassembled.

Another object of the invention is to provide a tie that will firmly hold the rails in 25 place when the track is in service, while at the same time permitting them to be quickly assembled or disassembled.

Another object of the invention is to provide a rail holder or clamp to clasp and hold one or a plurality of rails to the tie.

With the foregoing objects outlined and other objects in view which will appear as 30 the description proceeds, the invention consists in the novel features hereinafter described in detail, illustrated in the accompanying drawings and more particularly pointed out in the appended claims.

Referring to the drawings:—

Figure 1 is a view partly in section of the invention with parts assembled.

Fig. 2 is a plan view of the tie and plate,

Fig. 3 is an end view of the tie and the plate.

Fig. 4 is a view similar to Fig. 1 with two rails instead of one held in the clamp; and,

Fig. 5 is a perspective view of a portion of a track with the rails at one end reversed and clamped together as shown in Fig. 4.

In the drawings, 1 represents a tie which 50 is conveniently made in I-shape, there being a channel formed by the web and side flanges both above and below the web connecting the side flanges.

Securely fastened to the tie 1 by suitable

devices as countersunk rivets or screws 3 is 55 a plate or clamp 2. This plate 2 is preferably thick enough to fill the upper channel so that the rail may rest both on the plate and upper edge of the tie flange. The plate 2 at one end is bent up to embrace the 60 base of a rail 4 as shown in Figure 1. The other end 5 of the plate extends a considerable distance to the left (Fig. 1) of the rail base 4 and is bent upwardly and then toward the rail to provide a loop to hold a 65 block 6 suitably shaped to snugly fill the loop and to rest on the base of the rail and fit up against the side of the rail to be held between the bent up end 5 and the web 7 of the rail when the parts are assembled. 70

The block 6 may be of wood or other suitable material and is adapted to be driven between the bent-up end 5 and the web of the rail to secure the rail in place on the tie. 75

The rails are frequently used as tracks for coal mining machines and when the machine needs to be moved to follow the coal supply it frequently happens that the tracks may be extended slightly by reversing the 80 rails as shown in Figs. 4 and 5, putting a bottom flange 4 above a preceding rail and to thus provide a track for running the machine the short distance necessary to keep up with the coal supply. In this case the 85 upper part of the rail is held as shown in Fig. 4, between the loop 5 and the web 7 of the rail by the block 6. Of course sufficient space must be left between the loop 5 and side 7 of the rail to allow the insertion of the 90 additional rail from above downwardly.

When the parts are assembled as shown in Fig. 1 the lower flanges of the I-shaped tie will extend into the ground or material on which it rests which will tend to hold the tie securely in place; the web forming an extended base and the plates or clamps with the interposed block securely holding the rail to the tie, there being some give between the parts while holding them securely together. To disassemble the parts it is only necessary to drive the block 6 which may be slightly wedge-shaped, from its position shown in Fig. 1 when the tie may be moved to the right in Figure 1 far enough to release the base of the rail from the short bent up end of the plate 2 and then the rail may be lifted off the tie. 105

The advantages of the construction are apparent to those skilled in the art and need not be further specifically pointed out.

What I claim is:

5. 1. A tram road comprising a tie, a rail having a comparatively narrow head and a comparatively wide flanged base, a plate secured to the tie and turned up at one end to clamp one side of the flanged base, said 10 plate being turned up at its other end to form a loop, and a block fitting in said loop, there being space sufficient between the side of the rail and the loop to allow the insertion of the top of another rail in the loop 15 for the purpose described.
2. A tram road comprising a tie I-shaped in cross section, a rail having a base, a plate secured in the channel of the tie and having an end embracing the rail base on one side 20 and a loop on the other side of the rail, and means in the loop for firmly holding the rail in the embrace of the plate.
3. A tram road comprising a tie I-shaped in cross section, a rail having a base, a plate 25 having a thickness approximately equal to the depth of the channel in the tie and secured to the tie in said channel, said plate having one end embracing the rail base, a loop on the other side of the rail, and a block resting in the loop for firmly holding the rail in the embrace of the plate.
4. A tram road comprising a tie, a rail having a base, a plate secured to the tie and embracing the base of the rail on one side, 35 said plate having a loop on the other side of the rail, and a removable block resting in the loop and against the rail to normally hold the rail in the embrace of the plate, whereby upon the removal of the block, the tie may be moved endwise to release the rail from the embrace of the plate.
5. A tram road comprising a tie I-shaped

in cross section, a plate secured to the channel of the tie, a rail having a base resting on the plate, said plate embracing the rail base on one side, its other end extended beyond the rail base and terminating in a loop, and a removable block normally resting in the loop and against the side of the rail.

45 6. A tram road comprising a rail having bottom flanges and ties, one or more sections of the road having rails turned upside down and resting on other rails and a clamping plate having turned up ends, a short turned 50 up end embracing one flange to hold a rail to a tie, said plate being fastened to the tie, and a wedge block inserted between a side of the rail and the other turned up end of said plate, the construction being such 55 that when the block is removed, the rails 60 may be lifted from the clamping plates.

7. A railway and tie comprising a body member, and rail clamps secured to said body member at the extremities thereof, 65 said clamps being formed from single strips of metal and having straight body portions contacting flatly with the extremities of said body member and extending longitudinally thereof, means for securing said 70 clamps to said body member, tongues rising from one of the extremities of the body portions of said clamps and disposed at acute angles thereto, said tongues being adapted for engagement with the base flanges of 75 rails, arms rising from the other extremities of the body portions of said clamps and having their upper extremities curved towards said tongues for engagement with rail holding wedges.

80 In testimony whereof I hereunto affix my signature.

LEONARD SARGEANT.
